UNITED STATES PATENT OFFICE.

THOMAS F. MECHLING, OF WILKINSBURG, PENNSYLVANIA.

VACUUM-SIPHON.

1,250,928.

Specification of Letters Patent. Patented Dec. 18, 1917.

Application filed June 8, 1917. Serial No. 173,571.

To all whom it may concern:

Be it known that I, THOMAS F. MECHLING, a citizen of the United States, residing at Wilkinsburg, in the county of Allegheny 5 and State of Pennsylvania, have invented certain new and useful Improvements in Vacuum-Siphons; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in vacuum siphonages and particularly to devices of this kind used by surgeons for producing a vacuum within certain 20 tubes to accomplish the drainage of various organs of the human body after certain operations have been performed.

The primary object of this invention is to provide a device of this character which 25 will cause a suction through suitable delivering tubes, by the passage of fluid from one fluid chamber to another.

Another object of the invention is the provision of means for varying the force of 30 the suction of the apparatus. A still further object of the invention is to connect and support a pair of fluid tanks in such a manner that they may be easily and quickly reversed, thereby producing a continuous 35 siphonage action.

I illustrate my invention in the accompanying drawings, in which:—

Figure 1 is a perspective view of the apparatus positioned ready for use.

Fig. 2 is a longitudinal section view of the venting valves and Fig. 3 is a detail view of the pivoted latch and connections.

Reference now being had to the details of the drawings by numerals, 5 indicates a suitable support having a vertically extending pipe 6, each end of which is provided with a pivoted latch member 7 engaging the catch portions 8 formed on the top of the respective tanks 9 and 10. Disposed 45 centrally of the pipe 6 is a pipe 11 forming an axle on which the member 12 revolves. The member 12, as clearly shown is arranged intermediate of the length of the supporting rod 13, which is secured to tanks 9 and 10 by 50 suitable clamps 14. The tanks 9 and 10 are disposed one above the other, the adjacent

extremities of which are tapered as at 15, and are connected by a pipe 16, the passage of fluid through said pipe 16 being controlled by the needle valve 17. 60

Connecting the tanks 9 and 10, at a point adjacent to the tapered portions 15 thereof, is a pipe 18 having a central coupling 19, in which are the valve seats 20 and 21, connected by a short pipe 22, having a venting 65 opening 23. The ball valves 24 are adapted to seat on the respective seats 20 when the apparatus is moved to certain positions.

A pipe 25 connects the opposite ends of the tanks 9 and 10 by means of the substantially short pipes 26, and the flow of liquid therethrough is controlled by the needle valves 27 and 28 positioned at the point of connection between pipes 26 and tanks 9 and 10. Adjacent the outer ends of the 75 pipes 26 are openings 26' to receive the respective plugs 35 which, when removed and the valves properly operated, permit the water to be drained from the tanks.

A strong or mild vacuum may take place 80 by manipulation of the valves, a mild vacuum with the valves almost closed, and a strong vacuum with the valves more open. When the water shows a tendency to leave the lower part of the gage of upper tank, the 85 tanks are swung on their pivot 11 to the reverse position, and the valves are set to permit the vacuum to take place in the upper tank, while the lower valve or valve at the base of the lower tank is closed. It will, of 90 course, be understood that the drainage from the patient is not drawn into the tanks, but the tanks merely create a suction through the delivering tubes which are in communication with a bottle or other suitable receptacle 30', in such a manner that the drainage 95 will be delivered thereto.

The connecting pipe 29 is in communication with the pipe 25, and is disposed intermediate its length whereby the pipe 29 is 100 always above the water level in the lower tank to permit of an unobstructed passage being had between the connecting pipe 29 and the tank in which the vacuum is being created. To the connecting pipe 29 the 105 usual flexible delivery tubes 30 are connected, these tubes 30 providing communication between the pipe 25 and patient undergoing the operation. The filling of the tanks 9 and 10 is accomplished by removal 110 of the cap 31 of the upper tank, whereupon the fluid is put into the tank, there being a

cap 31 on each tank. In order to determine the amount of fluid in the tanks 9 and 10, the gages 32 are provided and it will be readily seen that the operation of the fluid passing from one tank to the other may be observed at all times.

In the operation of the device, the delivering tubes are positioned within the patient's body, the valves 17 and 28 closed, the cap 31 of the uppermost tank removed and the uppermost tank filled with liquid. After the tank has been filled, the valve 17 is then slightly opened to permit the water in the upper tank to pass to the lower tank, thereby producing a vacuum in the upper tank and consequently forming a suction in the delivery tubes which results in the drainage of the organs in which the delivery tubes are positioned.

20 What I claim to be new is:—

1. In a surgical apparatus, a frame, a pair of tanks pivotally supported by the frame, means for communication between the tanks, means for controlling the flow of fluid from one tank to the other, means for providing communication between the outer ends of the tanks, a connecting pipe in communication with the last mentioned means, said connecting pipe being disposed in a plane

with the axis of the tanks, and means for 30 venting one of the tanks.

2. In a surgical apparatus, a supporting frame, a pair of communicating tanks mounted on the support, means for mounting the tanks to permit the same to revolve 35 on the stand, means for holding the tanks stationary with relation to the stand, a pipe for providing communication between the tanks, said pipe being arranged exteriorly thereof, valves for controlling the passage 40 of fluid into the tanks, a valve for controlling the passage of fluid from one tank to the other, and means for venting the tanks.

3. In a surgical apparatus, a supporting frame, tanks revolvably supported on the frame and arranged one above the other, means on the support and coöperating with the tanks for holding the tanks stationary 45 with relation to the stand, means for permitting the fluid of one tank to pass to the other tank to cause a vacuum in one of the tanks, and means for venting the lower tank.

In testimony whereof I hereunto affix my signature in presence of two witnesses.

THOMAS F. MECHLING.
